UNITED STATES PATENT OFFICE.

WILLIAM W. RIDGELY, OF HEART LAKE, PENNSYLVANIA, ASSIGNOR, BY MESNE ASSIGNMENTS, TO RIDGELY HEATER COMPANY, OF SCRANTON, PENNSYLVANIA, A CORPORATION OF NEW JERSEY.

HEATER.

Application filed December 22, 1924. Serial No. 757,467.

This invention relates to heaters adapted to be used more particularly for burning culm and other fine coal although it is equally useful in burning coarser coal if desired.

The main object is to support the fire box in the combustion chamber in such manner as to provide an extra supply of fresh heated air to the surface of the fuel at various levels for the purpose of increasing the combustion of the fuel and also for burning practically all of the gases released from the fuel and thereby to reduce to a minimum the smoke content of the escaping products of combustion and to greatly increase the temperature of the heat developed from a given quantity of fuel.

In other words, I have sought to produce a more economic combustion of the solid fuel and the gases generated therefrom so as to increase the resultant heat and reduce the smoke content of the escaping products.

One of the specific objects is to support the fire box in the combustion chamber in such manner as to provide vertical air passage between the walls of the fire box and combustion chamber from the ash pit to the top of the fire box and also to provide the walls of the fire box with openings there-through the major portion of its length or height so that fresh air may pass from the space around the fire box through the openings to the fuel at varying levels and also across the top of the fire box in case the latter should be filled with fuel so as to heat the air in transit to the fuel for increasing combustion of the fuel and gases.

Another object is to make the fire box in sections and to provide suitable means whereby they may be supported and locked in operative position upon an underlying supporting ring carrying the grates which form the bottom of the fire box.

Other objects and uses relating to specific parts of the device will be brought out in the following description.

In the drawings:

Figure 1 is a top plan of a detached fire box embodying the various features of my invention, the front ends of the manually operated grate bars being broken away.

Figure 2 is a vertical sectional view taken on line 2—2, Figure 1, showing a portion of the combustion chamber and ash box in sec-

tion and the fire box in operative position 55 therein.

Figure 3 is a horizontal sectional view taken in the plane of line 3—3, Figure 2.

Figure 4 is a perspective view of a detached grate supporting ring.

Figure 5 is a perspective view of one of the detached fire box sections.

As illustrated this heater comprises a shell —1— forming a combustion chamber —2— in which is placed a fire box —3— having a supporting ring —4— resting upon suitable lugs —5— of the ash box —6—, said ring being provided with means for supporting a series of grate bars —7— which are connected to each other by gears 70 —8— for simultaneous rocking movement, the intermediate grate bars being provided with extensions —9— through the front side of the ash box for manual operation by a suitable shaker, not shown.

The fire box —3— is mounted within the combustion chamber —2— and, aside from the ring —4—, is composed of a series of similar upright segments —3'— arranged edge to edge in close juxtaposition around a 80 common, vertical axis and having the lower ends of their adjacent edges provided with downwardly extending lugs —10— which are seated in suitable openings —11— in the ring —4— to hold the segments in fixed relation to the ring against relative lateral or circumferential movement and at the same time permitting said sections to be withdrawn upwardly from the ring or replaced downwardly into operative connection 90 therewith without disturbing the ring from its normal position.

The object in making the main body of the fire box in sections is to permit them to be more easily placed in operative position 95 upon the grate ring or removed therefrom through the fuel door of the heater.

The supporting lugs —5— for the grate ring —4— are arranged in circumferentially spaced relation to permit the free passage 100 of air from the ash box —6— upwardly between them.

The marginal edge of the ring —4— is provided with a series of vertical openings —12— therethrough communicating with 105 the spaces between the lugs —5— to permit the passage of air therethrough from the ash box upwardly between the walls of the

fire box and combustion chamber, said ring being also provided with suitable bearings —13—, open at the top for receiving and supporting the movable grate bars —7—.

5 The portions of the ring —4— at the outer sides of the grate bars —7— have vertical openings therethrough for cooperation with the grate bars —7— in allowing the ashes to sift therethrough into the underlying ash box.

10 The upper end of the fire box sections are provided with laterally projecting flanges —15— having vertical openings —16— therethrough communicating with the space 15 between the walls of the fire box and those of the combustion chamber.

15 The major portion of the fire box sections between the flanges —15— and grate ring —4— are arranged in spaced relation to the 20 adjacent walls of the combustion chamber to form an air chamber or passage —17— communicating with the passages —12— and —16— and thereby affording a free passage 25 for the atmospheric air from the ash box —6— upwardly to the portion of the combustion chamber above the fire box.

30 The intermediate portions of the fire box sections between the grate ring —4— and flange —15— are also provided with lower and upper series of lateral openings —18— and —18'— therethrough and preferably elongated vertically and arranged in uniformly spaced relation circumferentially to allow the air to pass from the chamber 35 —17— to the surface of the fuel at various levels according to the amount of fuel present in the fire box.

35 The flanges —15— on the upper ends of the fire box sections extend laterally into 40 close proximity to the inner walls of the combustion chamber which serve to hold the sections against undue lateral displacement while permitting them to be readily removed or replaced vertically upon and from 45 the grate ring.

50 The grate ring is preferably made as a single unit and in some heaters may be readily placed in operative position upon its supporting lugs —5— through the fuel door but, in case the fuel opening is not sufficiently large to permit it to be passed therethrough, it may be installed upon the top of the ash box before the superstructure is placed in operative position after which the 55 fire box sections may be installed in operative position upon the grate ring through the ash box.

60 When the fire box is properly installed in the manner described and the remaining parts of the heater are otherwise completed to form the combustion chamber —2— the solid fuel may be placed in the fire box upon the grates —7— and —7'— to any level 65 within the height of the fire box so that

when ignited and burning the atmospheric air which is admitted to the ash box is free to pass upwardly through the grates and fuel into the fire box and also upwardly through the passages —12—, —17—, and —16— to the portion of the combustion chamber above the fire box for increasing the combustion at the surface of the fuel when the fire box is filled or in case the level of the fuel is at varying distances below the top of the fire box the air from the chamber —17— may pass through the openings —18— or —18'— to such level for increasing the combustion of the gases at the surface of the fuel and incidentally reducing to a minimum the smoke content of the escaping products of combustion.

70 This construction and arrangement of the fire box within the combustion chamber in the manner described has proven to be highly efficient, not only in the economic combustion of the solid fuel, but also in producing complete combustion of the gases at the surface of the fuel thereby conserving the fuel and at the same time obtaining the greatest amount of heat therefrom.

75 What I claim is:

In a heater for burning solid fuel, an ash box having its top provided with an opening and lugs projecting inwardly from the walls of the opening in circumferentially spaced relation to form vertical air passages between them, an outer shell mounted on the top of the ash box and surrounding said opening at the outside of the vertical air passages, a grate ring loosely supported on 80 said lugs and provided with a central grate-opening and diametrically opposite journal bearings open at the top, the outer marginal edge of said ring being provided with a circumferential series of vertical air passages 85 registering with the air passages between the lugs, grate bars journaled in said bearings and removable through the upper open sides thereof and a fire box having its lower end loosely supported on the ring between the central opening and the vertical air passages in the marginal edge of the ring and in spaced relation to the shell to form an air chamber between the fire box and shell 90 communicating with the vertical passages in the ring, said fire box having its upper end provided with an outwardly projecting marginal flange forming the top wall of said air chamber, and provided with additional vertical air passages therethrough communicating 95 with said chamber, the intermediate portion of the fire box being provided with lateral air passages therethrough to permit the passage of air from said chamber to the fuel within the fire box at different levels.

100 In witness whereof I have hereunto set my hand this 17th day of December, 1924.

105 WILLIAM W. RIDGELY.
